UNITED STATES PATENT OFFICE.

CHARLES P. BOOTH, OF ATLANTIC CITY, NEW JERSEY, ASSIGNOR OF ONE-HALF TO SAMUEL SNELLENBURG, OF PHILADELPHIA, PENNSYLVANIA.

DESIGN FOR A BOTTLE.

SPECIFICATION forming part of Design No. 20,135, dated September 9, 1890.

Application filed July 31, 1890. Serial No. 360,569. Term of patent 14 years.

To all whom it may concern:

Be it known that I, CHARLES P. BOOTH, a citizen of the United States of America, residing at Atlantic City, in the county of Atlantic and State of New Jersey, have invented a certain new and original Design for Bottles; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 In the drawing, the figure is a perspective view of a bottle which illustrates my design.

The leading feature of the design consists in a bottle in the shape and configuration of a coffin and provided at one end with a neck 20 having a stopper-opening.

A refers to the upper portion of the bottle, which represents the foot portion of a coffin, and upon the face of the same is formed a representation of a skull and cross-bones. The edges of the upper and lower face of the 25 bottle have at intervals formed projections representing coffin nails or screws, (referred to by b,) while the sides of the bottle have formed thereon projections c, representing handles. The lower front face of the bottle may have 30 either a raised or sunken panel, as d.

I claim—

A design for a bottle, substantially as herein shown and described.

In testimony whereof I affix my signature in 35 presence of two witnesses.

CHARLES P. BOOTH.

Witnesses:

SAMUEL SNELLENBURG,
ADOLPH EICHHOLZ.
